(57) **CLAIM**

The ornamental design for a wearable LED hair regrowth device, as shown and described.

DESCRIPTION

FIG. 1 illustrates a front perspective view of a wearable LED hair regrowth device;

FIG. 2 illustrates a bottom perspective view of the wearable LED hair regrowth device thereof;

FIG. 3 illustrates a front view of the wearable LED hair regrowth device thereof;

FIG. 4 illustrates a back view of the wearable LED hair regrowth device thereof;

FIG. 5 illustrates a left side view of the wearable LED hair regrowth device thereof;

FIG. 6 illustrates a right side view of the wearable LED hair regrowth device thereof;

FIG. 7 illustrates a top view of the wearable LED hair regrowth device thereof; and,

FIG. 8 illustrates a bottom view of the wearable LED hair regrowth device thereof.

The broken lines shown in the drawings are included for illustration purpose only and form no part of the claimed design.

1 Claim, 8 Drawing Sheets
